UNITED STATES PATENT OFFICE

MICHAEL J. WAREK, OF PLAINS, PENNSYLVANIA

AUTOMATIC POULTRY FEEDING DEVICE

Application filed November 2, 1927. Serial No. 230,616.

This invention relates to an automatic poultry feeding device, the general object of the invention being to provide means for permitting feed to drop from a hopper upon a scattering device at predetermined intervals of time so that feed will be furnished to the poultry automatically at stated intervals without manual aid, except that the hopper must be refilled from time to time.

10 Another object of the invention is to provide means for regulating the time at which the device will operate so that the feed will be scattered every hour, every half hour or at any other suitable period of time.

15 A further object of the invention is to provide a normally closed valve for the hopper, with magnetic means for opening the valve and a clock having means associated therewith for controlling the circuit of the magnetic means.

20 This invention also consists in certain other features of construction and in the combination and arrangement of the several parts, to be hereinafter fully described, illustrated in the accompanying drawings and specifically pointed out in the appended claim.

25 In describing my invention in detail, reference will be had to the accompanying drawings wherein like characters denote like or corresponding parts throughout the several views, and in which:—

Figure 1 is an elevation of the device.

Figure 2 is a plan view thereof.

30 Figure 3 is a vertical sectional view through the upper portion of the device.

Figure 4 is a fragmentary sectional view showing the valve in open position.

35 Figures 5 and 6 are views of the circuit controlling means on the clock.

40 In these views, 1 indicates a scattering device which is supported in elevated position by the legs 2, this device being of substantially conical form, with rounded wings 3 at each corner thereof to increase the scattering effect. Holes 4 are formed in the device and the metal cut to form the holes is bent upwardly at the lower edges of the holes to form stops 5 to direct some of the material through the holes. Thus some of the feed-

ing material will pass through the holes and drop under the scattering device, while the main body of the material will drop from the edges of the scattering device.

45 A pair of uprights 6 have their lower ends adjustably connected with the scattering device and their upper ends support a hopper 7 which is provided with a conical-shaped bottom having its lower end cut off to provide the outlet opening 8. A rod 9 passes through

50 a centrally arranged sleeve 10 in the hopper and through the central portion of the scattering device and a valve member 11 has its hub part 12 fastened to the lower portion of the rod, a tiltable valve member 13 having a hole at its center considerably larger than the hub, resting upon the valve member 11, with its hole passing over the hub. A coil spring 14 is placed on the rod between the valve member 11 and the apex of the scattering member, though I prefer to attach a V-shaped brace 15 to the lower end of the hopper and to provide the bight of the same with a boss 16 which enters an opening in the apex

55 of the scattering member and which receives the end of the valve stem 9 so that the hopper and its valve parts can be lifted off the scattering member and the parts will remain in place. The hopper is provided with a false bottom of conical shape, as shown at 17, for preventing the full weight of the feed material in the hopper from coming against the valve members, as the spring is relied upon to hold the valve members in closed position.

60 By having the tiltable member 13, this member will adjust itself to permit grains of large dimensions to pass from one side of the hopper opening while grains of smaller dimensions are passing through the opposite side thereof.

65 I provide magnetic means for opening the valve, the support for such means being shown at 18. Such support is carried by a post 19 adjustable as to its length, as shown at 20 and having its lower end slidably connected with the scattering member through the pin and slot connection shown generally at 21. The magnet is shown at 22 and the armature arm at 23, this arm being pivoted to a part of the support and being normally

held with its inner end raised by means of an adjustable spring 24 which connects the outer end of the arm with a part of the support. A set screw 25 is carried by the inner end of the arm and is adapted to engage a disk 26 fastened to the upper end of the valve stem or rod. The usual make and break means 27 are used to give the arm an oscillatory movement as long as the current is on.

10 A battery B is electrically connected with one terminal of the magnetic means and the framework of a clock C is electrically connected with the other terminal of the magnetic means. A transparent plate 28 of non-conducting material is placed over the face of the clock and carries a central terminal 29 which is electrically connected with the battery. Movable arms 30 have their inner ends pivotally connected with said terminal 29 and stationary terminals 31 are carried by the plate 28 and are adapted to be engaged by the outer ends of the arms when the arms are moved to a certain position. The inner ends of the terminals 31 carry spring contacts 32 which are adapted to be engaged by a spring contact 33 on the minute hand 34 of the clock. Thus during the revolution of the minute hand, the contact strip 33 will contact with all the strips 32 of the terminals 31, but unless an arm 30 is in engagement with a terminal 31, nothing will happen. If an arm 30 is in engagement with a terminal 31, however, the current to the magnetic means will be closed through the central terminal 29, the arm 30, terminal 31, strip 32 and strip 33 on the minute hand, through the frame of the clock to the magnetic means. Current will continue to flow to the magnetic means as long as the strip 33 on the minute hand is in engagement with a strip 32 of a terminal 31 and as the magnetic means are provided with the usual make and break device, the valve will be opened and closed quite a number of times before the circuit is closed. Thus 45 a quantity of feed will pass from the hopper over the scattering device, which will scatter it in the litter around and under the device. By having some of the feed drop through the scattering device, the fowls will scratch in the litter under the device as well as that to the sides thereof. By having the disk 26 on the top of the valve rod, the magnetic means will engage the disk even though the parts are slightly out of alignment.

50 55 From the foregoing it will be seen that this device will furnish feed to the poultry at predetermined intervals so that it is not necessary to have an attendant to feed the poultry, though, of course, the hopper must be refilled whenever necessary. The clock can be set to cause the device to come into operation at any desired time so that the poultry can be fed at any desired time. The parts are adjustable to secure the most efficient operation and by having the uprights 6 and

19 adjustably connected with the scattering device, hoppers of different sizes can be used with the device.

It is thought from the foregoing description that the advantages and novel features of my invention will be readily apparent. 70

I desire it to be understood that I may make changes in the construction and in the combination and arrangement of the several parts, provided that such changes fall within the 75 scope of the appended claim.

What I claim is:—

A poultry feeding device comprising a hopper having a discharge opening therein, a valve for controlling the opening and including a stem extending through the hopper, a bracket arm supported by the upper end of the hopper and projecting horizontally therefrom, a support arranged beneath the hopper, a post including relatively adjustable sections connecting the bracket arm with the support, a magnet mounted upon the bracket arm, an armature arm therefor mounted for pivotal movement on said bracket arm, a spring connecting one end of the armature arm with the adjacent end of said bracket arm and normally maintaining one end of the armature spaced above the valve stem, and a circuit for the magnet, whereby movement of the armature arm will cause an opening and 95 closing movement of the valve.

In testimony whereof I affix my signature.
MICHAEL J. WAREK.
